FIG. 2

FIG. 1

INVENTOR.
O. L. BABCOCK
BY Milton L. Randall

ATTORNEYS.

UNITED STATES PATENT OFFICE.

OMAR L. BABCOCK, OF WINNEBAGO, NEBRASKA.

DEMOUNTABLE-RIM TOOL.

1,263,510.

Specification of Letters Patent. Patented Apr. 23, 1918.

Application filed June 9, 1917. Serial No. 173,905.

To all whom it may concern:

Be it known that I, OMAR L. BABCOCK, a citizen of the United States, and resident of Winnebago, in the county of Thurston and State of Nebraska, have invented certain new and useful Improvements in Demountable-Rim Tools, of which the following is a specification.

The present invention relates to demountable rim tools.

The invention has for its primary object the production of an improved tool for contracting and expanding demountable rims to facilitate the demounting and remounting of the tires.

Another object of the invention is the production of an improved demountable-rim tool embodying extensible and retractable means for expanding and contracting the rim and adapted to be actuated by the usual automobile jack.

Still another object of the invention is the production of a demountable-rim tool embodying extensible and retractable means for expanding and contracting the rim and adapted to be operated in either direction by the extending of an automobile jack.

With these and other objects in view, the invention consisting in the construction, combination and novel arrangement of parts will be fully understood from the following description reference being had to the accompanying drawings, which form a part of this application and in which like characters of reference indicate corresponding parts throughout the several views, of which,—

Figure 1 is a side elevation of a demountable rim with the device of my invention applied thereto and showing a jack as used in connection with the device; and

Fig. 2 is an enlarged plan of the device, parts being cut away.

Although I have illustrated and herein-after described the preferred embodiment of the invention I would not be understood as being limited to the specific structure chosen for illustration for various alterations and modifications in the details of construction and arrangement of parts may be made without departing from the spirit and scope of the invention as defined in the appended claims.

Referring, now, to the illustrations, the device consists of an extensible and retractable frame including two pairs of parallel rods, 3 and 4, slidably freely through cross

bars, 5 and 6. Into the cross-bars are threaded set-screws, 7 and 8, the former being engageable with the rods 4, to releasably secure the said rods to the cross-bars, and the latter being operable to similarly engage the other rods.

The outer end of each rod is preferably interconnected with its mate by a cross-member, 9, to provide means engageable with the inner periphery of the rim to expand the rim. In the present embodiment the rods of each pair are formed integrally with a cross-member 9, forming substantially a U-shaped frame member. At their angles, 70 the U-shaped members are formed with eyes 10, in which are pivoted eyes 11, formed on the shanks of rim-engaging hooks, 12.

When the set screws, 8, of the bar, 5, and the set-screws 7, of the bar, 6, are tightened 75 and the other set-screws all loosened, it is evident that movement of the bars from each other will retract the frame members, while if the said set-screws 8 and 7 are loosened and the other set-screws tightened, movement 80 of the bars from each other will extend the frame members.

In operation the tool is applied as shown in Fig. 1 the hooks of the frame members being engaged with diametrically opposite 85 sides of the rims. A jack is then interposed between the cross-bars. The jack illustrated is a familiar form of vehicle jack including a support, 13, carrying an extensible post, 14, and a lever, 15, oscillation of which extends the post.

It is now clear the jack operates to force the bars from each other to extend or retract the frame members, according as which set-screws are tightened.

Having thus described my invention what I claim as new and desire to secure by Letters Patent of the United States, is—

1. A demountable-rim tool comprising two pairs of parallel rods, means on the rods engageable with the inner and outer faces of a rim, two cross-bars slidably supporting the rods, and means for releasably engaging each pair of rods with either cross-bar, whereby relative movement of the cross-bars in one direction will extend or retract the rods, according to the respective engagement of the rods and cross-bars.

2. A demountable-rim tool including two pairs of parallel U-shaped rods, relatively so disposed that their cross-members are at their remote ends to engage the diametri-

cally opposite sides of the inner periphery of a rim, two cross-bars through which the rods are free to slide, hooks on the rods engageable with the outer periphery of the rim, and means for releasably engaging each pair of rods with either cross-bar whereby relative movement of the cross-bars in one direc-

tion will extend or retract the rods according to the respective engagement of the rods and cross-bars.

In testimony whereof, I have hereunto set my hand this 28th day of May, 1917.

OMAR L. BABCOCK.
